UNITED STATES PATENT OFFICE

BRUNO REICHELT, OF NUTLEY, NEW JERSEY

TEMPERATURE-CONTROLLED RELEASE FOR FIRE-EXTINGUISHING GRENADES

Application filed October 31, 1929. Serial No. 403,809.

In general terms, my present invention has to do with the provision of novel means for releasing fire extinguishing substance automatically upon the occasion of rise in temperature above a certain predetermined point due to the presence of fire in the vicinity of my invention; and more particularly it is my purpose to provide a device of this character wherein a grenade is employed to contain suitable fire extinguishing substance, and which is releasably held in novel frame means through the instrumentality of fusible connections in the frame structure which are acted upon by the heat generated by a starting fire to release the grenade which thereupon falls and is shattered by contact with any hard object in its path to free the fire extinguishing substance contained therein. My present invention is a duplicate of my forfeited application Ser. #38874, filed June 12, 1925, allowed January 26, 1927, with Figure 3 cancelled.

I am aware that fuse devices have been employed in the art especially in connection with automatic sprinkler systems, but my present invention resides particularly in that combination which automatically releases a grenade from a symmetrical frame of pleasing appearance and extremely simple design and construction, thereby dispensing with all valves, piping, pumps, and other intricate mechanism which is usually associated with systems of the aforementioned type. My grenade furthermore, is so carried in the frame that it is protected from accidental jolts and jars, and since the frame is something more than a bracket retainer which must first be mounted on a base, it is not necessary to carefully instruct a person in its use; it may simply be hung up on a ceiling or wall bracket or projection and when so disposed will act automatically in case of fire to release the grenade.

My frame is formed by novelly bending a single strand of wire to provide a retaining bail and a side protecting rib for a grenade as well as two loops or eyes for hanging the frame respectively either to a wall or ceiling or a room; third, the support for the grenade formed with more than one fusible connec-

tion so that it is necessary for more than a spasmodic rise in temperature to obtain before my grenade will be released, thereby avoiding accidental release of the same; fourth, my frame is especially designed to support an artistic screen, or fabric covering so that the artistic appearance of a room in a dwelling, theatre or the like will be preserved; fifth, my grenade support is formed with plural pivoted or hinged sections which are designed to "fall away" upon fusing of the connections, thereby eliminating the disadvantages of so called "spring" releases.

The structural elements employed to accomplish the above and other results and objects will be hereinafter more fully described in detail and pointed out in the claims appended hereunto and forming a part of the specification, but the scope of my invention may only be determined by the limits defined in the claims.

In the accompanying drawings wherein is illustrated the preferred embodiment of my invention:

Figure 1 is a side view of my fire extinguishing device supported from a wall or other perpendicular surface;

Figure 2 is a side view of my fire extinguishing device supported from a ceiling or other horizontal surface;

Figure 3 is a perspective view of my grenade frame;

Figure 4 is a plan view of the supporting member of my frame and shows the fusible connections for its pivoted sections, and

Figure 5 and Figure 6 show approved ways of suspending my grenades and shielding the same to afford a pleasing and artistic appearance.

In the drawings wherein like characters of reference designate like or similar parts throughout the several views:

The frame *e* for my grenade is formed of a single strand of wire bent to provide an annular side protecting rib *e'* around the 95 grenade, a loop or eye *e2* for hanging the frame on a wall or other perpendicular surface, and a bail *e3* over the top of the grenade. Intermediate the ends of the bail *e3* is a second loop or eye *e4* for suspending the 106

grenade from a ceiling or other horizontal surface. The remaining portions of the wire strand form the hangers *e*5 which extend down from the protecting rib *e*' to a point 5 adjacent the small end of the grenade *a*, and the respective terminals thereof are hooked as at *e*6 to retain there-between a support for the grenade. The support is formed of similarly and semi-circularly bent sections 10 of wire *e*7 and *e*8, each of which is retained by the hooked end *e*6 of the hangers, and the two sections normally register with each other to form an annular band about the small end of the grenade with their respective free ends adjacent to the retained ends of the opposed section. These ends are fixed by fusible solder connections *e*9 so that the sections will be released to swing down or "fall away" to discharge the grenade when 20 the temperature rises above the fusing point of the fusible solder connections *e*9 such as would be the case were a fire to start in the vicinity of the grenade and frame.

When my grenades are disposed about a 25 dwelling, church, theatre, or other building where artistic appearance is a consideration, they may be shielded by fabric shades *f*, similar to lamp shades, and in mounting my grenades on ceilings or the like decorative 30 brackets or hooks *g* may be used. When supported on a wall or the like hook supports such as designated at *h* have been found practical and desirable.

While the operation of my fire extinguishing 35 device is believed to be apparent from the foregoing, emphasis is here made of the fact that it is entirely automatic in its operation, needs no instructions or skill in its disposition and use, is exceedingly simple in 40 construction, and pleasing in appearance.

While in the foregoing, there has been illustrated and described such combination and arrangement of elements as constitute the preferred embodiment of my invention, it is 45 nevertheless desired to emphasize the fact that interpretation of the invention should only be conclusive when made in the light of the subjoined claims;

Having described my invention and its objects with such attention to detail as will 50 thoroughly acquaint one skilled in the art with its construction and advantages, I claim:

1. A frame for supporting a fire extinguishing 55 grenade comprising a bent wire retaining body formed of a single strand, said wire being bent to form a protecting rib, a top bail, and a plurality of eyes extending from the top bail, a support carried by the retaining body 60 and pivoted at its ends to the respective terminals of the wire forming the body, said support being formed in sections adapted to swing to release a grenade and fusible connections for the sections to normally retain 65 a grenade in the frame.

2. An article of manufacture for use in retaining fire extinguishing grenades comprising a frame formed of a single strand of wire, said frame having an annular rib, and depending hangers, the wire forming the same 70 being bent about itself to form elements constituting each a half of the annular rib, and the respective terminals constituting the hangers, the intermediate portion of one element being bent to form the bail, and plurally looped intermediate the extremities of the bail to form eyes for suspending the frame.

3. Means for releasably supporting a fire extinguishing grenade comprising similarly 80 formed wire members including a pivot end and a free end and adapted to be pivoted each to one end of a supporting frame and designed in assembly to support a grenade, said members being bent semi-circularly in opposite directions intermediate their extremities and registering thereat to form a circular seat for a grenade, the free terminals of each of the members being fusibly connected to the other adjacent the pivot end of the latter 90 each said wire member being adapted to swing downwardly about its pivoted end upon breaking of the fusible connection to release the grenade.

In testimony whereof, I affix my signature 95 hereunto.
